TUBE TURNER FOR PLUG MILLS

George E. Moore, Pittsburgh, Pa., assignor, by mesne assignments, to Blaw-Knox Company, Pittsburgh, Pa., a corporation of Delaware

Application June 9, 1955, Serial No. 514,273

2 Claims. (Cl. 80—11)

This invention relates to apparatus for the manufacture of seamless tubing and more particularly to apparatus for turning tubes about their own axis in a tube rolling mill of the type known as a plug mill.

Plug mills are used extensively in the manufacture of seamless tubing and comprise a two-high roll stand having grooved working rolls for rolling the tubing; a mandrel bar for supporting a mandrel or plug in the pass of the working rolls; a pair of stripping rolls, which are grooved to correspond to the working rolls, for removing the tube from the mandrel; a receiving table embodying a trough for supporting a tube on the entering side of the rolls, and a pusher for pushing the tube into the roll pass. In the conventional operation of a plug mill, a reheated pierced billet is deposited in the trough of the receiving table, the pusher shoves the billet into the pass of the working rolls over the mandrel, and the revolving work rolls draw the tube rapidly over the mandrel reducing the diameter and wall thickness of the tube and elongating it. As soon as the tube has passed through the working rolls, the mandrel is removed from the mandrel rod, the working rolls are separated, and the stripper rolls are engaged with the tube and move the tube rapidly in the opposite direction off of the mandrel rod, through the space between the working rolls and into the trough of the receiving table.

The grooves in the working rolls are not semi-circular but are flared or oval in order to prevent the edges of the grooves from damaging the tube as it passes through the work rolls. Accordingly, after the first pass through the mill the tube is slightly oval with its major axis in a horizontal plane and with greater wall thickness in the regions at the ends of major axis than in the regions at the ends of the minor axis; it is therefore necessary to rotate the tube 90° about its longitudinal axis and pass it through the plug mill again in order to make it approximately round and with a substantially uniform wall thickness throughout.

Accordingly, in ordinary practice, after the tube has been subjected to the first pass through the mill, an operator grasps the tube with a pair of tongs and rotates it through approximately 90°. Then the pusher is actuated to push the tube into the roll pass again and the rolling and stripping cycle is repeated. The tube, which is still at a bright red heat, is then discharged from the receiving table and progressed to further operations.

The operator who has the task of rotating the tube after the first pass through the mill must work between the working roll stand and the end of the receiving table, a location that is extremely hot and not without hazard. The conditions under which the operator must work are so severe that ordinarily an operator is expected to work only 15 minutes out of each hour and it is therefore necessary to have four men just to rotate the tubes between the first and second passes through the plug mill.

The object of the present invention is to provide an effective mechanism for grasping and turning the tube as it rests in the trough of the receiving table between

2

passes through the plug mill. In the preferred form of my invention this object is carried out by providing a pair of grippers or tongs which are actuated to grasp the tube upon its being returned to the receiving table, are then rotated substantially about the axis of the tube to rotate the tube through approximately 90°, and are then released from the tube so that the tube can be repassed through the mill.

A preferred form of the invention is illustrated in the accompanying drawing, in which

Figure 1 is a side elevational view of a receiving table embodying my invention showing the associated plug mill in vertical section.

Figure 2 is a plan view of the apparatus shown in Figure 1.

Figure 3 is a transverse sectional view illustrating the tube turning mechanism, the section being on an enlarged scale and taken as indicated by lines 3—3 of Figures 1 and 2.

Figure 4 is a sectional detail on an enlarged scale taken as indicated by line 4—4 of Figure 3.

Figure 5 is a sectional detail illustrating the cylinder for actuating the gripping tongs and taken as indicated by line 5—5 of Figure 3.

Figure 6 is a view similar to Figure 3 but on a larger scale and with some of the parts broken away.

Figure 7 is a plan view of the tube turning mechanism shown in Figure 3, and

Figure 8 is a sectional detail taken as indicated by line 8—8 of Figure 3.

Referring particularly to Figures 1 and 2 of the drawings, the invention is illustrated as it may be adapted for use with a plug mill indicated in general at 10 and having upper and lower working rolls 11 and 12 mounted in roll stand 13. Immediately behind the working rolls 11 and 12 are stripper rolls 14 and 15 which are mounted in a suitable roll stand 16. As shown best in Figure 2, the working rolls 11 and 12 are conventionally provided with a plurality of slightly oval grooves 18, so that the mill can roll tubes of different diameters, and the stripper rolls are also grooved, as indicated at 19 in Figure 1, to correspond with the main rolls. A water cooled mandrel bar 21 is supported to project between the rolls and support a mandrel or plug 22 in the pass of the working rolls 11 and 12.

As indicated by the arrows, Figure 1, the working rolls are driven so as to draw the tube over the mandrel and bar and the stripper rolls are driven in the opposite direction so as to return the tube to the working table. The apparatus is so arranged that only one pair of rolls may be in contact with the tube at any given time.

Work pieces are supplied to the working rolls and received from the stripping rolls by a receiving table indicated generally at 24. The table 24 includes a trough 25 for guiding the tube and a pusher 26 actuated by a fluid pressure cylinder mechanism 27 for pushing the tube into the pass of the working rolls. The trough preferably is made up of a plurality of sections of longitudinally extending strips 82. The entire receiving table is supported upon a frame work of longitudinally extending beams 29a, 29b, 29c, and 29d (Figure 3), the lower pair of which are supported on pairs of longitudinally spaced wheels 30 (only one pair being shown in the drawing) which run on transverse rails 30a. Positioning mechanism 31 moves the table on the rails so that the trough 25 may be aligned selectively with any of the grooves 18 of the working rolls.

In order to supply tubes to the mill, a plurality of skids 32 are secured to and extend outwardly from one side of the receiving table. The skids are adapted to receive the hot tubes which are brought to the receiving table for working in the mill. A plurality of stops 33,

downwardly rotatable by shaft 34, are disposed along the table on the same side as the skids 32 and control the entry of the tubes, by gravity feed, into the trough 25. Fluid pressure cylinder 35 actuates shaft 34. A plurality of discharge arms 36, upwardly rotatable by the shaft 37, 5 are disposed along the other side of the receiving table. The arms 36 normally underlie the trough 25 between the sections 28 and are adapted to lift the tubes out of the trough and discharge them from the table and mill after they have been worked. The shaft 37 and arms 36 are actuated by fluid pressure cylinder 38.

All of the elements heretofore described may be of conventional construction and per se form no part of the present invention.

In the conventional operation of a plug mill constructed or described above, a hot tube is brought to the mill and deposited upon the skids 32 where it remains, resting against the stops 33, until the same are rotated downwardly to permit the tube to roll into the trough 25. The tube is then pushed into the pass of the working rolls, which are in working position, and is drawn over the mandrel by the rolls; the working rolls are then separated and the stripper rolls engaged with the tube to return it to the table. An operator stationed between the working rolls and the end of the receiving table 15 then grasps the tube with tongs and rotates it about 90°; thereafter, it is again passed through the mill and returned to the trough. The cylinder 38 is then actuated to rotate the arms 36 upwardly and discharge the tube from the table.

According to the present invention, a mechanism is incorporated in the apparatus for rotating the tubes about their own axis for approximately 90° between successive passes through the working rolls 11 and 12.

The apparatus for turning the tubes is preferably disposed near the end of the receiving table adjacent the mill rolls and is indicated in general at 45. As shown particularly in Figures 3 and 6, the tube turning apparatus comprises a pair of tongs or grippers for grasping the tube, which are mounted on a carriage, and means to move the carriage along an arcuate track and thereby turn the tube.

More particularly, the preferred embodiment of my invention comprises a pair of gripper arms 47 and 48 having opposed gripper jaws 49 and 50 which are adapted to engage and grasp a tube lying in the trough. The arms 47 and 48 extend laterally away from the axis of the tube and the ends of the arms 47 and 48 remote from the jaws are pivotally supported for pivotal movement about axes parallel to the axis of the tube as at 51 and 52 in a carriage 54 and are also geared together as by teeth 55 and 56 so that the jaws 49 and 50 are constrained to rotate about the pivots 51 and 52 in equal angular amounts and in opposite directions.

The jaws are moved toward and away from each other or into and out of engagement with tube by means of a double acting fluid pressure cylinder and piston mechanism which is mounted between the arms 47 and 48, see Figures 3, 5 and 6. The cylinder 58 is mounted on arm 47 by means of trunnions 59 and the piston rod 60 is secured to arm 48 by wrist pin 61. Fluid under pressure is supplied to the cylinder through appropriate conduits and the arrangement is such that admission of fluid on the side of the piston nearer the arm 48 will force the piston further into the cylinder and will move the arms 47 and 48 and jaws 49 and 50 toward each other about the pivots 51 and 52 so as to cause the jaws to grasp and clamp the tube, whereas admission of fluid on the other side of the piston will push the piston further out of the cylinder and move the arms and jaws apart, releasing 70 the tube.

Preferably, the jaws 49 and 50 are detachable from the arms 47 and 48 so that jaws of appropriate size for the tubes being worked may be used.

The carriage 54 provides means for rotating or turn-

ing the tube 90° about its own axis once it has been grasped by the jaws. To this end, I provide wheels or rollers 65 at both ends of the carriage 54 and an arcuate track indicated generally at 66 on which the wheels 65 operate. The track 66 is supported by the table frame members 29a and 29b and preferably has its center coincident with the axis of an average sized tube, as determined by the capacity of the mill, lying in the trough 25.

As shown particularly in Figures 4 and 8, the track preferably comprises vertical outer arcuate webs 67 and 68 which support arcuate flange members 69 and 70, and inner vertical track members 71 and 72 which in turn are secured to an arcuate plate 73 having openings 73a therein. The wheels or rollers 65 are retained between and roll or travel upon the oppositely disposed surfaces 74 of the flange members 69 and 70, and 75 of the inner track members 71 and 72.

A plurality of arcuately spaced supports 76 and 77 support the inner track members 71 and 72 and the adjacent webs 67 and 68 respectively in proper spaced relation. The spaces between the supports, and the openings 73a permit the discharge of scale and dirt that might otherwise accumulate inside of the box-like track structure. Plates 80 at the ends of the track, vertical plates 82 and plates 83 form rigid channel structures at each end of the track. Plates 80 and 82 are for stiffening the structure. The travel of the trolley is limited by the stroke of the cylinder 92. The track 66 is conveniently of welded construction as indicated. The plates 83 are 30 welded to the webs 67 and 68 and are bolted to the upper flanges of beams 29a and 29b to support the track.

In order to provide for movement of the carriage along the track, a pin 84 (see Figures 6, 7 and 8) is secured to the frame members 85 of the carriage 54 and 35 projects beyond the carriage on either side thereof. Connecting rods 86 are pivotally secured to the ends of pin 84 and these, in turn, are pivotally connected to lever arms 87 mounted on shaft 88. Shaft 88 is supported in a suitable bracket 89 on the entry side of the delivery 40 table and is rotated by a crank arm 90 which is actuated by the piston rod 91 of a double acting fluid pressure cylinder and piston 92 mounted in trunnions 93 on bracket 89. Movement of the piston out of the cylinder causes the connecting rods 86 to pull the carriage 54 along the tracks 66 from the position shown in full lines in Figure 6 to the position shown in broken lines in Figure 6. The carriage and the gripper jaws are thus rotated substantially 90° about an axis disposed within the trough 25 and substantially coincident with the axis of the tube, and a tube engaged by the gripper jaws is likewise rotated substantially 90°, or one quarter turn.

The operation of a plug mill embodying a preferred form of my invention is substantially the same as that described above except for the tube turning mechanisms.

55 The cylinder 58 is actuated to open or separate the jaws 49 and 50 and keep them open when the tube is delivered to the trough 25 from the skids 32 and when the tube is returned to the trough after a pass through the mill. After the first pass is completed and the tube has been 60 returned to the receiving table, the cylinder 58 is actuated to move the arms 47 and 48 toward each other and cause the jaws 49 and 50 to grip the tube. With the tube thus gripped, the cylinder 92 is actuated to move the carriage 54 along the track through 90 degrees of arc thereby rotating the tube in the manner hereinbefore 65 described. The cylinder 58 is then actuated to separate the jaws and release the tube, whereupon the tube is again passed through the rolls and returned to the receiving table for discharge therefrom.

As it normally does not matter whether a tube is rotated 90° to the left or right, between successive passes through the mill, the carriage may be kept in its new position until after the next tube has completed its first pass through the mill and the apparatus is then actuated to turn the next tube in the opposite direction.

However, if it is desired to rotate each tube in the same direction, the carriage may be returned to its initial position each time a turn is completed.

Although I have illustrated and described a specific form of my invention, various changes and modifications thereto will occur to those skilled in the art, all within the precepts of my invention, and I do not care to be limited in the scope of my patent to the precise embodiments herein particularly illustrated and described.

I claim:

1. In apparatus of the type described, guide means adapted to support a tube, an arcuate track having its center substantially coincident with the axis of a tube supported on said guide means, a carriage mounted on said track, tube grasping means carried by said carriage, said tube grasping means comprising a pair of arms pivotally mounted on said carriage and being geared together at one end and having opposed jaws at the other end adapted to engage a tube supported on said guide means and a fluid pressure cylinder and piston means acting between said arms to move said jaws toward and away from each other, and a fluid pressure motor for moving said carriage on said arcuate track thereby to rotate a tube grasped by said jaws substantially about its own axis.

2. In apparatus of the type described, guide means adapted to support a tube, an arcuate track having its

center substantially coincident with the axis of a tube supported on said guide means, a carriage mounted on said track, tube grasping means carried by said carriage, said tube grasping means comprising a pair of arms pivotally mounted on said carriage and being geared together at one end and having opposed jaws adapted to engage a tube supported on said guide at the other end and power means for moving said jaws toward and away from each other, and power means for moving said carriage on said arcuate track.
